DISPOSABLE RAZOR

Kenneth Tuthill Grafwohl, 508 Sterling Place,
Greenport, N.Y.
Filed June 9, 1959, Ser. No. 819,038
6 Claims. (Cl. 30—32)

This invention relates to safety razors and particularly to those safety razors which are meant to be of a disposable nature.

The primary object of this invention is the provision of an improved safety razor.

Another object of the invention is the provision of an improved safety razor wherein the razor blade is permanently in place in the body of the razor.

Another object of the invention is the provision of an improved safety razor wherein the razor blade is incorporated within the construction of the razor body when the latter is cast of suitable material such as plastic.

Another and further object of the invention is the provision of a safety razor utilizing a half portion of a regular double-edge razor blade by casting two razor bodies around one blade and breaking the double-edge razor in two along weakened lines near the ends of the blade, so that when finished, there will be one half a two-edge razor in each of two razor bodies.

Another and still further object of the invention is the provision of a safety razor blade with a smooth bar on the approach side of the body of the razor adjacent the blade itself and having a support for the middle of the bar and being cut away to permit unobstructed approach to the blade.

Still another object of the invention is the provision of an improved safety razor having holes in the top and bottom of the body portion made by registration of pins or other projections which hold the blades in position while the casting of the body portion takes place.

A still further object of the invention is the casting, simultaneously of two razor bodies about a double edge safety razor blade in such a manner that when the casting is completed, the blades may be readily severed in two pieces, leaving a half blade in each razor body with its cutting edge in position to function properly.

Still another and further object of the invention is the provision of an improved razor cast with a slightly tapered handle integral with the body of the safety razor, the handle having a tapered hollow interior.

Referring to the drawing wherein is illustrated an embodiment of my invention,

FIGURE 1 is a side view of my invention.

FIGURE 2 is a front view of the invention looking directly toward the cutting edge of the safety razor blade.

FIGURE 3 is a detail cross sectional view on the line 3—3 of FIGURE 2.

FIGURE 4 is a detail cross sectional view on the line 4—4 of FIG. 2.

FIGURE 5 is a detail cross sectional view on the line 5—5 of FIG. 2.

FIGURE 6 is a top plan view of the pair of safety razors as they are cast together in one piece.

FIGURE 7 is a plan view of the whole safety razor blade as used in casting two razor bodies around it before the two halves of the razor blade are broken apart.

FIGURE 8 is an end view of the razor blade with the thickness dimension much exaggerated to show the grooves in the blade for the purposes of weakening it for easy separation after the two body parts are cast together around the razor blade as shown in FIGURES 6 and 9.

FIGURE 9 is an end view of the showing in FIG. 6.

FIGURE 10 is a detail view of the razor 18 being held in place by the pins 16b and 17c.

In carrying out this invention, each of two bodies of

2

two safety razors are cast around one half of a whole safety razor blade and after being fabricated in pairs, the razor bodies, held together by the whole razor blade, are broken apart, severing the razor blade at its ends or other weak parts, thus forming two complete razor bodies, each including the half blade about which it has been molded.

Referring in detail to the drawing, a handle 15 is provided for handling and control of the safety razor. This handle is hollow as shown in FIGURE 9 to reduce the amount of plastic or other material from which it is made and also to cause a more nearly uniform thickness to be obtained throughout the body of the razor.

On the upper end of the handle 15 is the razor body portion 16, which is here illustrated as being integral with the handle 15. In FIGURES 3, 4 and 5, the underside of the body member 16 is shown as having an indentation with a rim 17 on three sides, the front, and two ends to provide for the rigidity of the razor body as a whole.

In the top or face-contacting portion of the body portion and in the upper relatively large surface of the indentation in the body portion (see FIGS. 3 and 5) are oppositely placed holes 16a and 17b spaced opposite each other in pairs, and the spaces are caused by spacing pins 16b and 17c (FIG. 10) which retain the proper relative position of the safety razor blade 18 in the body space of the mold while the body portions of the pair of razors are being cast. The pins 16b and 17c are each four in number and also are shown as being placed with some of the pins 16b and 17c out of a straight line. These pins 16b and 17c together with the heads 19a (FIGS. 7 and 9) which extend between the two body members 16, and which are on the upper ends of the sliding pins 19, act to hold the razor blade in proper registration during the time the blades are being loaded prior to casting. Special attention is invited to the arrangement of these pins 16b and 17c which are preferably out of alignment. This bends the blade as well as holds it in proper relative position in order that the cutting edges of the two parts of the blade are in proper relation to the cooperating body parts, thus insuring that the cutting edges will be in the proper positions to perform the beard-cutting function in a satisfactory and predetermined manner. These pins 16b and 17c and parts 19, 19a are not a part of this invention, per se.

In the form of razor blade which I use, the cutting edge does not extend out the full length of the blade. As shown on FIG. 7, the cutting edge stops short of the length of the blade and there are provided four spaces caused by the cutaway corners 18c (FIG. 7) which allow for the provision of a guard portion on the body member of the razor which I have designated 17x which permits the passage of the razor over the skin of the user without injuring the skin. These guards are mere rounded points located in the spaces 18c when the razor blade is incorporated in the razor structure.

The blade 18, as preferably used, is similar in general construction and outline to the ordinary two-edge blade for use in the ordinary safety razor. It is provided with two cutting edges, a long opening 18m on its long center line which opening extends to within a short distance of the ends of the blade. At the ends of this opening 18m, there are two narrow connecting portions which I provide with weakened lines 18y as clearly shown on FIGS. 7 and 8. These weakened lines provide for a place where the two-edge razor blade may be broken in half to form the two blades of the separated razors after they have been cast, as is clear from FIGS. 6 and 9.

The action of the out-of-line arrangement of the adjusting pins 16b, 17c, assures a pressing downwardly by the upper pins, 16b and a pressing upwardly by the

lower pins, 17c on the upper and lower sides of the razor blade 18. And since there are two sets of pins 16b and 17c for each half of a complete safety razor blade, and since they are all set so as to press their respective surfaces of the razor blade, thus holding the blade in proper position, the proper placing of the blade is assured.

At the front of the safety razor body, 16, there is a forward rail 20 which forms a part of the rim 17 and extends the full length of the cutting blade.

The upper edge of this rail 20 is rounded for proper contact with the skin of the user. Its position with relation to the cutting edge of the blade is such that it will permit the skin of the user to be closely contacted by the blade but will prevent undue pressure of the cutting edge in a manner to cut the skin. As already pointed out, the ends of the safety razor blade are protected from cutting the user's skin by the guards 17x in the same manner that the edge 20 protects the skin of the user throughout the length of the cutting edge. At the center, adjacent the edge 20 is a bridge member 21 which strengthens the middle of the edge 20 and prevents the forward central portion of the rim 17 from bending. See FIG. 4.

In the manufacture of this safety razor, the whole blade is preferably placed over the head or edge 19a, in position on one part of the mold, not shown, so as to be in position to have the pins 16b, 17c hold the blade when the mold forms are closed. When this is done, the separating fin 19, at the upper edge of which is the head or edge 19a, extends between the positions of the two back faces of the pair of body portions and extends upwardly and through the opening 18m between the halves of the razor blade to hold it from sliding as the blade becomes held by the pins 16b, 17c. As the mold is closed with the pins 16b, 17c and the fin 19a, all in operation, the razor blade is held in its proper place for the casting of the plastic or other material used for making the body portions 16.

After the casting has taken place, it is obvious that there will be two complete safety razor bodies, 16, each body enclosing one half of the blade.

The handles of the two razors are tapered outside and inside to facilitate removal from the mould. The handle openings in the mold are provided with cores 45 which extend into the handles. These handles and their cores are removed after the casting operation.

The two bodies of the razors are held together by the weakened portions 18y shown in detail in FIG. 8. By pulling apart on the lower ends of the handles, as they 50 are shown in FIG. 9, the two razor bodies will break apart, which completes the manufacturing process.

In the manufacture of this razor, the parts of the mold are so closely placed that it is impossible for any of the plastic or other material of which the bodies are made, to get to the cutting edges of the blade and avoids the necessity of clearing away the material after manufacture.

While I have illustrated and described an embodiment of my invention in detail, it is to be understood that the disclosure is merely illustrative and that modifications and changes may be made without departing from the spirit of the invention and within its scope as claimed.

Having described my invention, a razor, what I claim is:

1. A safety razor construction comprising, in combination,

(a) a two-edge razor blade of a commercial type, the blade having a cut away portion on its center line along the long axis, leaving weakened connecting portions holding the two halves of the blade together,

(b) said razor construction having a pair of complete razor body portions,

4
(c) each of said body portions having a half of the said two-edge blade embedded therein, and each enclosing that part of the razor blade away from the cutting edge, the two body portions being separated along the cutaway portion of the razor blade and being separable from each other adjacent the weakened portion of the blade, for separating the two bodies and the blade halves from each other,
(d) a guard means adjacent the cutting edge of each half blade to protect the skin of the user.

2. A safety razor construction comprising in combination,

(a) a two-edge blade of a commercial type, the blade having a cut away portion on its center line along the long axis, leaving weakened connecting portions holding the two halves of the blade together,

(b) said two-edge blade having oppositely extending cutting edges,

(c) said safety razor construction having a pair of complete razor body portions, each enclosing that part of the razor blade away from the cutting edge, the two body portions being separated along the cutaway portion of the razor blade and being separable from each other adjacent the weakened portion of the blade, for separating the two bodies and the blade halves from each other,

(d) each of the body portions having a half of the said two-blade embedded therein and

(e) a guard means on each body portion to protect the skin of the user against being cut.

3. A safety razor construction comprising in combination,

(a) a two-edge blade of a commercial type, the blade having a cutaway portion on its center line along the long axis, leaving weakened connecting portions holding the two halves of the blade together,

(b) said safety razor construction having a pair of complete razor body portions,

(c) each of the body portions having a half of the said two-edge blade embedded therein, and each enclosing that part of the razor blade away from the cutting blade edge, the two body portions being separated along the cutaway portion of the razor blade and being separable from each other adjacent the weakened portion of the blade, for separating the two bodies and the blade halves from each other,

(d) a guard means adjacent the cutting edge of each half blade to protect the skin of the user against injury and

(e) integral parallel handles, one extending from each body portion.

4. A safety razor construction comprising in combination,

(a) a two-edge razor blade of a commercial type, the blade having a cut away portion on its center line along the long axis, leaving weakened connecting portions holding the two halves of the blade together,

(b) said razor construction having a pair of complete razor body portions,

(c) each of the body portions having a half of the said two-edge blade embedded therein, and each enclosing that part of the razor blade away from the cutting blade edge, the two body portions being separated along the cutaway portion of the razor blade and being separable from each other adjacent the weakened portion of the blade, for separating the two bodies and the blade halves from each other,

(d) a guard means adjacent the cutting edge of each half blade to protect the skin of the user against injury, and

(e) the two halves of the blade being in planes and at an angular relation to each other.

5. A safety razor construction comprising in combination,
- (a) a two-edge razor blade of a commercial type, the blade having a cut away portion on its center line along the long axis, leaving weakened connecting portions holding the two halves of the blade together, 5
- (b) said razor construction having a pair of complete razor body portions, each with a respective handle, 10
- (c) each of said body portions having a half of the said two-edge blade embedded therein, and each enclosing that part of the razor blade away from the cutting blade edge, the two body portions being separated along the cutaway portion of the razor blade and being separable from each other adjacent the weakened portion of the blade, for separating the two bodies and the blade halves from each other, 15
- (d) a guard means on each body portion to protect the skin of the user against injury and 20
- (e) the halves of the razor blade in each body portion being in respective planes at a predetermined angle to each other and
- (f) each blade half having a predetermined angle relative to its respective handle. 25
6. A safety razor construction comprising in combination,
- (a) a two-edge razor blade of a commercial type, the blade having a cut away portion on its center line along the long axis, leaving weakened connecting portions holding the two halves of the blade together, 30
- (b) said razor construction having a pair of complete razor bodies,

- (c) each of said bodies having a half of the said two-edge blade embedded therein, and each enclosing that part of the razor blade away from the cutting blade edge, the two body portions being separated along the cutaway portion of the razor blade and being separable from each other adjacent the weakened portion of the blade, for separating the two bodies and the blade halves from each other,
- (d) a guard means adjacent the cutting edge of each half blade to protect the skin of the user, and
- (e) a connecting bridge between the guard means and main portion of the body member of each razor to provide stability between the body's main portion and the guard means.
